FLAG DISPLAY MEANS

Harry M. Olson, Clear Lake, Iowa

Application August 2, 1955, Serial No. 525,951

4 Claims. (Cl. 116—173)

My invention relates to means for displaying flags on sidewalks, in yards and the like, and is designed as an improvement over the subject matter of my U. S. Patent, No. 2,263,138.

The primary object of my invention is to provide simple and practical means for displaying a flag at full or half mast and means for anchoring the staff in the ground or the like.

Another object is to provide improved means for suspending a flag on a flagstaff at full or half mast by a hem on the flag slidably mounting the flag on the staff for permanent attachment to the staff.

Still another object is to provide an improved base for the flagstaff on which the staff may be stood for storage or other purposes.

Still another object is to provide improved means for detachably anchoring the base to a concrete block adapted to be embedded in the ground or the like.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a view in side elevation of my invention with the flag at full mast;

Figure 2 is a fragmentary view in side elevation with the flag at half mast;

Figure 3 is an enlarged view in bottom plan of the base for the flagstaff;

Figure 4 is an enlarged fragmentary view in vertical section of the flagstaff, base and anchoring means;

Figure 5 is an enlarged fragmentary view in vertical section taken on the line 5—5 of Figure 1;

Figure 6 is an enlarged fragmentary view in vertical section of the flagstaff and suspending means;

Figure 7 is an enlarged fragmentary view in transverse section taken on the line 7—7 of Figure 1; and

Figure 8 is a fragmentary view in side elevation partly broken away and illustrating the flag furled on the lower section of the staff for storage purposes.

Referring now to the drawings by numerals, the flagstaff 1, as in my previous patent, comprises upper and lower tubular sections 3, 5 detachably connected together by a pin 7 and an ornamental knob 9 is threaded on a threaded stud 11 extending upwardly out of the upper end of said staff. The pin 7 is welded, as at 8, in the lower section 5 and the upper section 3 may be pulled off said pin to disassemble the flagstaff 1.

The base for the flagstaff 1 comprises an oblong, preferably oval metal base plate 13 with a rounded down-turned edge flange 15 and a tubular metal socket 17 rising therefrom and in which the lower end of the flagstaff 1 is removably inserted. The socket 17 is welded on the base plate 13, as at 19, in the longitudinal center of said plate and preferably to one side of the transverse center of the plate.

2

A hooked screw 21 depends through the base plate 13 in the longitudinal center thereof and at one side of the socket 17 and provides means on said plate for anchoring the same while resting on the ground to concrete block 23 embedded in the ground 25.

The concrete block 23 is preferably round and as in my aforesaid patent is provided with a central vertical, laterally pronged anchor rod 27 having an upper end eye 29 in a concavity 31 in the upper end of the block 10 and in which the hooked screw 21 is detachably inserted. A wing nut 33 on said screw 21 on top of the plate 13 provides for tightening said screw.

Leveling means for the base plate 13 comprises a pair of vertical screws 35 with lock nuts 37 thereon. The leveling screws 31 are located at one end of the base plate 13, on the opposite side of the socket 17 from the hooked screw 21 and opposite side of the longitudinal center of said plate and are engageable with the ground 25 to tilt said plate on its opposite end to level the base plate 20 and thereby plumb the flagstaff 1.

The flag 39, as in my aforesaid patent, is provided with a hem 41 at its inner edge by means of which it is sleeved on the staff 1 and vertically slidably attached to the flagstaff 1.

The suspending means for the flag 39 comprises a tape 43 of a length to extend vertically through and out of the hem 41, preferably being slightly longer than said hem. The tape 43 is provided at upper and lower ends thereof with grommets 45, 47 adapted to be applied over the stud 11 when the knob 9 is removed and to be clamped against the upper end of the flagstaff 1 by said knob when the knob is replaced. The hem 41 is stitched at its upper end, as at 59, to the tape 43 adjacent the upper end of the tape. By this arrangement, the tape 43 may be pulled out of the hem 41 from its point of attachment to said hem to reverse said tape end for end for a purpose presently explained.

Referring now to the operation of my invention, when it is desired to display the flag 39 at full mast, the 40 grommet 45 at the upper end of the tape 43 is applied over the stud 11 so that said hem 41 is suspended by a short length of the tape 43 from said stud and the remainder of said tape hangs free through said hem, all as shown in Figure 1.

To display the flag 39 at half mast, the tape 43 is pulled out of the hem 41 to reverse it end for end and the grommet 47 is applied over the stud 11 in place of the grommet 45, whereby the hem 41 is suspended by a long length of the tape 32 and slides down the staff 1 to position said flag at half mast, as shown in Figure 2.

The base plate 13 may be detached from the concrete block 23 by loosening the hooked screw 21, and the screw 21 withdrawn into said plate together with the screw 35. Then, the staff 1 may be rested on a floor or the base plate 13 for storage in upright position. As shown in Figure 8, the tape 43 may be detached from the stud 11 so that the hem 41 will slide down onto the lower section 5 of the flagstaff 1 and be furled in said lower section and then, the upper section 3 of the flagstaff 1 55 may be pulled loose from the pin 7 to shorten the shaft for storage.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

70 What is claimed as new is as follows:

1. Means for displaying a flag comprising an upright flagstaff, a flag having a hem slidably sleeved onto said

staff, a tape secured intermediate its transverse center and one end to said hem to provide long and short portions on said tape at opposite sides of its point of securement to said hem, and terminal means on said tape and the upper end of said staff for attaching the long and short portions of the tape to said upper end selectively to lower and raise the flag on the staff.

2. Means for displaying a flag comprising a flagstaff having a base plate adapted to rest on the ground, a hook on said plate at one side of the flagstaff for pivotally attaching said plate to an anchor in the ground, screw feed means on said plate at the opposite side of the flagstaff engageable with the ground to pivot and level said plate, a flag having a hem slidably sleeved on said flagstaff for raising and lowering, and a tape secured intermediate one end and its transverse center to said hem to provide long and short portions on said tape at opposite sides of its point of attachment to said hem, and terminal means on the tape and the upper end of said staff for attaching the long and short portions of the tape to said upper end of the staff selectively to lower and raise the flag on the staff.

3. Means for displaying a flag comprising an upright flagstaff, a flag having a hem slidably sleeved onto said staff, a tape secured intermediate its transverse center and one end to said hem to provide long and short portions

on said tape at opposite sides of its point of securement to said hem, terminal means on said tape and the upper end of said staff for attaching the long and short portions of the tape to said upper end selectively to lower and raise the flag on the staff, said means on the ends of the tape comprising grommets, said means on the upper end of the staff comprising a stud.

4. Means for displaying a flag comprising an upright flagstaff, a flag having a hem slidably sleeved onto said staff, a tape secured intermediate its transverse center and one end to said hem to provide long and short portions on said tape at opposite sides of its point of securement to said hem, and terminal means on said tape and the upper end of said staff for attaching the long and short portions of the tape to said upper end selectively to lower and raise the flag on the staff, said tape being reversible end for end for attachment to the means on the upper end of the staff.
